UNITED STATES PATENT OFFICE.

PETER L. YOUNGREN, OF WASHINGTON, DISTRICT OF COLUMBIA, ASSIGNOR
TO THE CHISHOLM, BOYD & WHITE COMPANY, OF ILLINOIS.

BRICK-KILN.

SPECIFICATION forming part of Letters Patent No. 556,295, dated March 10, 1896.

Application filed March 2, 1895. Serial No. 540,329. (No model.)

To all whom it may concern:

Be it known that I, PETER L. YOUNGREN, a subject of the King of Sweden and Norway, residing at Washington, in the District of Columbia, have invented a new and useful Brick-Kiln, of which the following is a specification.

This invention relates to that class of continuous or perpetual brick-kilns in which the operations of water-smoking, burning, setting, and taking out the bricks are carried on simultaneously and continuously, the necessary heat being produced partly by direct firing among the material in the kiln-compartments and partly by firing in a supplementary furnace.

In a similar prior invention for which a patent was granted to me in the United States under date of April 3, 1894, No. 517,637, is shown and described a supplementary furnace in combination with a main hot-air and heat flue, for the purpose of reinforcing the direct draft through the kiln to prevent condensation and discoloring of the brick. In the said patent the same main flue serves the purpose of conveying hot air from the cooling brick as well as to convey the heat from the supplementary furnace to the various kiln-compartments.

The present invention provides a new arrangement of flues, by the use of which the supplementary furnace is rendered more effective and its heat used independently of or in conjunction with the heat produced by the direct firing.

The principal objects of the present invention are, first, to provide means for treating one or more independent compartments with pure hot air simultaneously with treating one or more independent compartments with heat from the supplementary furnace; second, to provide means for thoroughly expelling the water from the brick in independent compartments before admitting them to the direct draft through the kiln; third, to provide means for regulating the temperature of the heat-currents departing from the main heat-flue, so that a portion of the heat generated in the supplementary furnace can be used for water-smoking in certain compartments at a low temperature simultaneously with using a portion of it at a higher temperature for re-

inforcing the direct draft in another compartment; fourth, to provide means for deflecting the direct draft toward the outer walls of the compartments without the construction of underground flues or draft-openings in or near the outer walls; fifth, to provide a kiln of simple and durable construction, and which will be efficient and give satisfactory results.

To this end the kiln consists of the sundry novel arrangements of parts hereinafter more fully described and particularly pointed out in the claims, reference being had to the accompanying drawings, in which—

Figure 1 is a top view of the kiln with a horizontal section of the supplementary furnace and of the smoke-stack on the line X X of Fig. 3. Fig. 2 is a plan section of the improved kiln on the line Y Y of Fig. 4. Fig. 3 is a vertical section on the line Z Z of Fig. 1, on a larger scale. Fig. 4 is a vertical cross-section on the line X Y of Fig. 1, looking to the left. Fig. 5 is a vertical section of the central portion of the kiln on the line Z Y of Fig. 3, looking to the right. Fig. 6 is a vertical section similar to Fig. 5 on the line A A of Fig. 1. Fig. 7 is a cross-section on the line B B of Fig. 1. Fig. 8 is an enlarged view, in section, showing the compensating joint between the covering and the kiln-walls before the firing takes place. Fig. 9 is a view of the parts shown in Fig. 8 after the firing and when the covering has settled, due to the shrinkage of the material in the kiln.

The kiln consists of a continuous-burning chamber 27^a of oblong form, inclosed between the central flue-walls 18 and the surrounding perpendicular walls 19, and is adapted to be divided, by means of temporary partitions 20, into a number of sub chambers or compartments, the number of which will vary according to the size and the capacity of the kiln, sixteen being shown and indicated by the numbers 1 to 16, inclusive.

In order to provide a kiln of simple and durable construction and which will enable the work of setting and taking out the brick to be performed with greater ease, the sides of the kiln-compartments are built perpendicular and closed at the top by a temporary covering which rests upon the brick after they

are set. This covering consists of two or more courses of brick 21 and 22 laid flatwise, with a dressing of clay or earth 23 on top. In this covering are formed feed - openings 24 at 5 proper distances apart for the introduction of fuel, and a hopper 25 having a cover 26 is placed over each of said feed-openings. This temporary covering is moved from time to time as the process of setting and taking out 10 the bricks requires, being taken from a compartment of cool burned brick and placed over a compartment of newly-set brick. In this manner the work of setting and removing the brick is facilitated by admitting plenty of air 15 and light to the workmen in the empty compartments.

In the drawings is shown a kiln divided into sixteen compartments. Each compartment is provided with a separate ingress-flue 27 20 opening into the compartment at or near one end thereof and a separate egress-flue 28 opening into the compartment at or near the opposite end of the compartment. Said ingress and egress flues open into the compartment 25 on the inner side near the floor thereof. It is preferred to locate the ingress and egress flues a distance equal to the length of one or two bricks from the partitions 20 in order to protect these latter, which are made from paper. 30 Between the inner walls, 18, constituting the inner sides of the compartments and in a horizontal plane above the aforementioned ingress and egress flues are located the three main flues 29, 30, and 31. Centrally between the 35 ends of these main flues is located the smoke-stack 32. The main flue 29 serves as a main draft-flue, and for that purpose communicates with the stack 32 and is provided with damper-controlled communications 33 with each 40 of the compartment egress-flues 28. It will be noticed that the main draft-flue 29 is provided with a lateral extension 34 at one end for the purpose of affording communication between the egress-flue 28 of the compartment 45 9 and said main flue. The central main flue 30 serves as a main hot-air flue to facilitate the conduction of hot air from certain parts of the kiln to certain other parts, and for that purpose is provided with the upwardly-extending branch flues 35 terminating at the 50 top of the kiln, at which point they are provided with covers or seals 36. The said main flue 30 is also provided with damper - controlled communications 37 with each of the 55 ingress-flues 27 leading into the kiln-compartments.

By removing the covers 26 over a series of the feed-hoppers 25 in the kiln-covering and placing a suitable hood 38 over said openings 60 and connecting said hood by means of a conveyer 39 with one of the branch flues 35 of the main hot-air flue 30 communication is obtained between the tops of the kiln-compartments and the said main hot-air flue 30. 65 This main hot-air flue 30 pierces the base of the stack without connecting with the flue thereof. (See Fig. 6.)

The main flue 31 serves as a main heat-flue for conducting heat from the supplementary furnace 40 to any desired kiln-compartment, 70 being in communication with the furnace through the downtake 41 and is provided with damper-controlled communications 42 with each of the ingress-flues 27 leading into the various kiln-compartments. It will be 75 seen that the ingress-flues 27 afford communication with each of the main flues 30 and 31, and the egress-flues 28 have communication with the main flue 29. Each of the ingress-flues 27 is provided with an air inlet or 80 passage 43 in communication with the outer atmosphere and with the said ingress-flue, said communication being controlled by a cover or seal 44. Immediately over the place where the downtake 41 enters the main heat-flue 31 is formed an opening 45, extending from the top of the kiln into said main flue 31, and a temporary seal 46 is placed over said opening 45. In the said main flue 31, under the aforesaid opening 45 and extending 90 part way therein, is placed an iron rod 47 in such a position that it can be observed by removing the cover 46 of the opening 45. By this means it can be readily ascertained when the heat in the flue 31 is too great for the 95 safety of the rods by means of which the various dampers are controlled, thereby enabling the heat to be controlled by regulating the fire in the supplementary furnace 40.

The central kiln-body, forming the inside 100 of the kiln-compartments, is enlarged at its ends, as shown at 48, for the purpose of deflecting the draft toward the outer walls of the end compartments and in some measure avoiding the short and direct course of the 105 draft along the inner sides of the extremities immediately adjoining the side compartments. The advantages of this arrangement of flues and parts will be fully appreciated after the operation of the kiln is understood, 110 which will be as follows: Assuming compartments 1 and 2 are empty for taking out the burned brick and setting in raw brick; compartments 3, 4, 5, 6, 7 and 8 containing burned brick in various stages of cooling, from those 115 entirely cool and ready to be taken out in compartment 3 to those white hot in compartment 8; compartments 9 and 10 are firing, fuel being introduced from the top through the feed-hoppers; compartments 11 and 12 120 are heating up preparatory to direct firing; compartments 13, 14 and 15 are water-smoking with furnace heat; and compartment 16 is heating up by hot air. All compartments containing brick are closed in by means of 125 the temporary covering and have their door-openings 49 sealed up. A paper curtain 20 is drawn across the end of compartment 16, preventing the outer atmosphere from entering said compartment from the empty compartment 1. Similar curtains are placed at the end of each compartment after the bricks have been set.

Opposite each ingress and egress flue an

opening or flue is formed in the brick, extending from inside to outside of the compartment, for the purpose of distributing the heat-currents across the compartment. The paper curtains above referred to are allowed to remain in position between the various compartments until the water-smoking is completed in each. In Fig. 2 said curtains are assumed to remain between compartments 1 10, 16, 16 15, 15 14, 14 13, and 13 12. After the water-smoking is completed in a compartment the curtain is burned out by means of a torch. The egress-flues 28 in each of the compartments 12, 13, 14, 15, and 16 are put 15 in communication with the main draft-flue 29 by opening the corresponding draft-dampers 33. The ingress-flues 27, leading into compartments 12, 13, 14, and 15, respectively, are put in communication with the main heat-flue 31 by opening the corresponding dampers 42. The cold-air inlets 43, connecting the ingress-flues 27 of the compartments 13, 14, and 15, are put in communication with the outer atmosphere by opening the corresponding 20 covers 44. The ingress-flue 27 leading into compartment 16 is put in communication with the hot-air flue 30 by opening its damper. The hot-air conductor 39 with its hood 38 is placed so as to connect the top of compartment 6 with the main hot-air flue 30. A fire is burning in the supplementary furnace 40 on top of the central kiln-body. It will now be seen that the outer atmosphere enters 25 the empty compartments 1 and 2 and is drawn through the compartments containing the cooling bricks, and in its course becomes gradually heated and at the same time it cools off the burned bricks gradually. In the compartments 9 and 10 this hot air supports the combustion of the fuel introduced therein, and the products of combustion are then drawn forward through compartments 11 and 12, heating the bricks and preparing them for subsequent firing. At the end of compartment 12 the 30 products of combustion are drawn into the main flue 29 and escape through the smoke-stack. The ingress-flue 27 of compartment 12 is discharging a heat-current from the supplementary furnace into said compartment, 35 which serves to reinforce the direct draft so as to heat up the bricks as rapidly as possible after the water-smoking is completed without forcing the direct draft through the cooling and burning compartments. The introduction 40 of this supplementary heat-current into the inner side of the compartment also serves the purpose of deflecting the direct draft toward the outer wall of the kiln-compartments, thus enabling a uniform distribution of the 45 direct draft and the heat from the supplementary furnace without the construction of underground flues or draft-channels in or near the outer walls.

Underground flues are objectionable aside 50 from being expensive to construct, because they are a source for the admission of moisture into the burning-compartments, being lo-

cated below the general grade of kiln and surroundings.

In the present invention the ingress and 70 egress flues are all located above the floor of the kiln and make the shortest possible connection with a common chimney, and without the aid of the supplementary heat-current this inside draft would naturally advance the 75 heat faster along the inside wall, which, of course, would be objectionable.

The supplementary heat-currents entering compartments 13, 14 and 15 are mingled with cold air after they leave the main heat-flue 80 and before entering the respective compartments, rendering them suitable for water-smoking purposes. It must be remembered that the temperature of the products of combustion emerging from the supplementary 85 furnace is maintained at about the same degree as the temperature of the direct draft at the point where the supplementary current mingles with said direct draft in compartment 12. It will therefore be seen that while the 90 same furnace and the same main flue serve to supply the various sub-currents entering the various compartments the temperature of each sub-current can be regulated to suit the requirement in each individual compartment, supplying currents of low temperature 95 to the water-smoking compartments at the same time it supplies a current of a higher temperature to reinforce the direct draft where the water-smoking is completed and it 100 is desired to heat up the bricks as rapidly as possible. While the process of water-smoking, burning, taking out and setting raw brick 105 is progressing, one compartment every day, the bricks water-smoking can be kept at the same temperature and under equal conditions for several days. This is of especial advantage in water-smoking dry-pressed brick, 110 which, being very dense in structure, prevent a free escape of the vapor from their interior. Hence the vapor, if formed too rapidly by the application of heat, will expand and disintegrate the raw brick.

It is obvious that a prolonged method of water-smoking can be carried on to a certain 115 extent with hot-air currents from the cooling bricks in other continuous kilns embodying a hot-air flue and branch flues connecting with the various kiln-compartments; but when an attempt is made in such kilns to draw sufficient hot air from the cooling brick to supply 120 several water-smoking sections, which, as stated, is necessary in the burning of dry-pressed brick, it is found that the temperature of the air passing directly into the burning-sections is reduced in proportion to the amount of heat withdrawn for water-smoking purposes, resulting in the withdrawal of the heat from the hot finished brick too rapidly, preventing a thorough annealing and necessitating a heavier firing in the burning-compartments in order to maintain the required 125 temperature; and this heavy firing is objectionable, inasmuch as it produces a high local

heat in and around the fireplaces formed in the brick, overburning and destroying the product.

- It is evident to any one experienced in the art that the higher the temperature of the feed-air can be maintained at the point where it passes from the hot finished brick into the burning-compartment the better are the results. It is found in practice that bricks are discolored by sulphur and other impurities contained in the products of combustion and mixed with vapor of water in the water-smoking compartments if allowed to condense among the brick, as by condensation these mixed gases are absorbed into the exposed surfaces of the bricks, giving them a permanent spotted, unsightly appearance. This discoloration occurs, more or less, when furnace-gases are led into a compartment containing coal-brick, the extent of the discoloration depending upon the temperature and amount of water present in the brick as well as upon the amount of sulphur in the fuel. In many instances it is necessary to use wood or coke in water-smoking or heating a kiln of brick, coal being subsequently used in the burning, because such fuel is comparatively free from sulphur. To prevent this discoloration of the brick in the present invention the newly-set brick is first treated with pure hot air, withdrawing a small amount of heat from the cooling brick for that purpose. After the bricks have once been heated by the pure hot air to the temperature desired for water-smoking the latter operation can be completed with furnace-heat without danger of discoloring the brick if such furnace-heat is only passed through the brick the length of one compartment, as in the present invention. If the water-smoke was carried from one compartment into another any great distance, (a compartment in this type of kiln generally ranging in length from fifteen to twenty feet,) the capacity of the gases, products of combustion, or simply hot air for carrying moisture will be exhausted before reaching the exit and condensation would occur. It will be seen that in the present instance the pre-heating with pure hot air is taking place in compartment 16, the hot-air conductor 38 being placed so as to connect the top of compartment 6 with the main heat-flue 30, and the ingress and egress flues of compartment 16 being connected, respectively, with the hot-air flue 30 and draft-flue 29, a current of hot air is caused to pass from the top of compartment 6 into the main hot-air flue 30, thence into and through said compartment 16 into the draft-flue 29. When placing the covering over a newly-set compartment, the upper course of brick 21 is not brought quite up to the furnace-walls and a brick 50 is placed in the space thus provided, the upper and lower sides of said brick being beveled upwardly and outwardly. The edges of this brick touch the furnace-walls and the edge of the course of

brick 21. Fig. 8 shows the position of this brick when the covering is first put on. During the burning and shrinking of the brick in the kiln it invariably occurs that the central portion of the kiln burns and settles ahead of the sides, causing the kiln-covering to part from the furnace-walls, as shown in Fig. 9, in which event the brick 50 is forced by its own gravity, assisted by the weight of the superincumbent earthy filling 23, tightly against the furnace-wall, preventing the escape of the filling and entrance of cold air into the kiln.

Bricks and tiles of rectangular sectional form have been used heretofore for the same purpose as the brick 50 in the present case; but it is found that when such rectangular bricks or tiles are placed at a sufficient angle to cover the space formed between the furnace-wall and the kiln-covering the lateral pressure of the filling causes the lower edge of such rectangular brick or tile to move outwardly and come flat against the furnace-wall when its lower support (the course of brick 22) descends during the settling of the kiln, and in that position is retained more or less by the unevenness of the surfaces allowing the filling to escape underneath said brick during subsequent settling of the kiln. The brick 50 provided for this purpose is of such form that when placed in position its entire weight falls outside of the lower supporting-edge, and that surface of the brick upon which the filling bears is nearer to the horizontal plane than that which passes through the extreme supporting-edges, causing the filling to exert a downward and outward pressure on the upper supporting-edge, while the lower edge is entirely relieved from any outward pressure. A compensating joint of the character herein set forth will be provided for each side of the covering bordering upon the outer and the inner furnace-walls.

It is obvious that in constructing a kiln embodying the essence of the invention changes in the form, proportion, and the minor details of construction may be resorted to without departing from the principle or sacrificing any of the advantages of this invention.

Having thus described the invention, what is claimed as new is—

1. In a continuously-operated kiln in which the bricks are burned by direct firing among the material, and which comprises independent compartments, a passage common to all the compartments and having communication with each, a second passage also having communication with each compartment, a supplementary furnace having communication with the said second passage, means for connecting the first passage with a compartment of burned and cooling brick, and with a compartment of newly-set brick to water-smoke the latter by pure hot air, damper-controlled passages for reinforcing this hot air by heat from the supplementary furnace, and a third passage having communication with the com-

partments and with the stack to carry off the vapors resulting from the water-smoking, substantially as described.

2. In a continuous kiln having a series of compartments formed by temporary partitions of combustible material, a series of flues arranged in parallel relation, and having communication with each of the said compartments, one flue communicating with the smoke-stack and with the egress-flues of each compartment, a second flue adapted to be put in direct communication with a compartment of burned and cooling brick, and with a compartment of newly-set brick to supply the latter with pure hot air for purposes of water-smoking, and a supplementary furnace in communication with the third-named flue, whereby its heat can be utilized to reinforce the direct draft through the compartments containing the brick which have been water-smoked, substantially as and for the purpose set forth.

3. A continuous kiln oblong in plan elevation and having a series of compartments formed between an outer wall and an inner central portion, and having the latter portion enlarged and made circular at its ends, the sides of the enlarged circular portions projecting beyond the walls of the said central portion to centralize the draft in the longitudinal compartments, substantially as set forth.

4. The herein-specified continuous kiln, having a series of separate compartments formed by temporary partitions of combustible material, a series of three flues arranged in parallel relation, each flue having direct communication with each of the said compartments by means of damper-controlled passages, one flue being in communication with the smoke-

stack and with the egress-passages of the said compartments, the second flue being adapted to be put in communication with a compartment of burned and cooling brick, and with a compartment of newly-set brick to supply the latter with pure hot air, a supplementary furnace having communication with the third flue, and with the ingress-passages of the compartments by means of the said flue, vertical openings having communication with the ingress-passages to temper the air from the supplementary furnace before it enters a desired compartment, and a metal rod located in the downdraft-passage of the supplementary furnace for the purpose of determining the heat from the supplementary furnace, substantially as and for the purpose set forth.

5. In a continuous kiln having a series of compartments, and having a central kiln-body provided with main flues above the kiln-floor, one flue being in communication with the stack, a supplementary furnace in communication with a second flue, ingress-flues, or passages, communicating with the said second flue and with one end of the kiln-compartments through the wall of the central kiln-body to deflect the direct draft outward, and egress-flues, or passages, communicating with the stack-flue and with the opposite end of the said compartments, all of the said flues being above the ground-floor of the kiln, substantially as and for the purpose described.

In testimony that I claim the foregoing as my own I have hereto affixed my signature in the presence of two witnesses.

PETER L. YOUNGREN.
